[57] CLAIM

An ornamental design for a tablet dispensing container, as shown and described.

DESCRIPTION

FIG. 1 is a front view of the tablet dispensing container;
FIG. 2 is a rear view thereof;
FIG. 3 is a right side view thereof;
FIG. 4 is a left side view thereof;
FIG. 5 is a top view thereof;
FIG. 6 is a bottom view thereof;
FIG. 7 is a front view shown with the lid in an open position;
FIG. 8 is a top view thereof;
FIG. 9 is a left side view thereof; and,
FIG. 10 is a side view thereof shown in use.
The broken line showing of the tablets and human hand is for illustrative purposes only and forms no part of the claimed design.

FIG. 5

FIG. 6

FIG. 3

FIG. 4

FIG. 1

FIG. 2

FIG. 10

FIG. 9

FIG. 7

FIG. 8
